CLAIM

The ornamental design for a paint can, as shown and described.

DESCRIPTION

FIG. 1 is a top, front and right side perspective view of a paint can showing my new design;

FIG. 2 is a rear view thereof;

FIG. 3 is a side view thereof;

FIG. 4 is a top view thereof; and,

FIG. 5 is a bottom view thereof.

The side opposite to that shown in FIG. 3 is identical thereto.
